UNITED STATES PATENT OFFICE.

BLANCH VIE-THEER, OF MARSHFIELD, OREGON.

TUMBLING-FIGURE TOY.

1,155,692.

Specification of Letters Patent.

Patented Oct. 5, 1915.

Application filed March 3, 1915. Serial No. 11,926.

To all whom it may concern:

Be it known that I, BLANCH VIE-THEER, a citizen of the United States, residing at Marshfield, county of Coos, and State of Oregon, have invented certain new and useful Improvements in Tumbling-Figure Toys, of which the following is a specification.

My invention relates to tumbling figure 10 toys.

The present invention is an improvement on those tumbling figure toys which comprise an elongated holder, dressed or configured to suit the fancy, in which is a rolling ball or sphere which produces, by its rolling movement and arrest, a tumbling or end-over-end movement when it is placed on any inclined surface.

My improvements consist, first, in the provision of an open ended cylinder with cloth, fabric or similar heads or ends therefor to receive the ball or sphere as it rolls to the respective ends of the cylinder; second, in a construction such as specified wherein the cloth, fabric, or similar head for the outer end of the cylinder is constructed or arranged, or designated as the head portion of the toy and the flexible cloth, fabric or equivalent head for the inner end of the cylinder constitutes a portion of the body or torso of the figure represented by the toy; third, a tumbling figure toy wherein the inner end of the tube or cylinder is provided with a flexible cloth, fabric or equivalent 35 head which is adapted to receive the rolling ball or sphere when the toy is held in an upright position or when it assumes such position, the distention of the said flexible head being thereby made to constitute a 40 portion of the torso or body of the figure represented by the toy.

As distinguished from those previously known tumbling toys employing a cylinder and a rolling ball or sphere, the open ended 45 cylinder construction and loose fabric or flexible head and bottom which I provide in my toy in combination with the rolling ball, gives to the toy a more lifelike and animated aspect than is possible with tumbling figure 50 toys having rigid or only slightly flexible solid heads for the cylinder and the attractiveness of the toy as an object of interest is thereby increased.

While I do not limit myself thereto, I preferably carry out the invention in a tumbling toy wherein the head of the figure

is provided by the fabric or loose diaphragm for the outer end of the shell or cylinder and the lower end of the body or torso is constituted by the inner, flexible, fabric head 60 or end of the shell or cylinder and the toy is preferably provided with flexible legs and arms and may have other clothing to enhance the attractiveness thereof.

My invention is fully described herein- 65 after and recited in the appended claims.

In the accompanying drawings: Figure 1 is a detail perspective illustrating the toy when tumbling down an incline surface; Fig. 2, an elevation of the toy; Fig. 3, a 70 vertical section thereof; and Fig. 4, a cross section, the arms being extended.

The body of the toy is provided with a tube or shell 1 of any suitable stiff and light material which is preferably made from a 75 blank bent into cylindrical form with its edges over-lapped as at 2 and secured by suitable fastenings such, for instance, as a cord 3. The tube or shell, as thus provided, is of cylindrical form and is entirely open 80 at its upper end 4 and lower end 5 so that the ball or sphere 6 may roll through the said open ends 4 and 5, but in practice, the ball or sphere 6 usually only partially projects through said open ends. I have found 85 celluloid to be well adapted for use as the body or shell 1, because it does not easily crack or break and has the requisite flexibility so that it will maintain the cylindrical form.

For the respective outer and inner open ends 4 and 5, I provide heads 7 and 8 of flexible material, such as cloth, or other fabric and as a convenient means of attaching these parts and also to assist in the dress or make-up of the toy, the cloth head 7 is extended for nearly the full length of the tube 1 or the full length thereof, if desired, in the form of a sheath or an envelop 100 completely covering said shell. The cloth end 8 is suitably connected to the envelop 9 by stitching 10. The envelop embraces the shell 1 sufficiently tight to maintain itself in substantially the position shown in Fig. 3.

In its broadest aspect, my invention is not limited to any particular form of dress of the toy and embraces the open ended shell 1 and the cloth or flexible heads 7 and 8 in combination with the ball or sphere 6 110 which is adapted to roll freely within the tube or shell 1 and into the heads 7 and 8.

I am well aware that the toy is complete and operative as thus constructed, even if having no superficial special contour or ornamentation. I prefer, however, to make 5 the toy in the simulation of a figure of more or less fantastic appearance. The outer portion of the envelop 9 may be provided with a face 11 and with a fringe of hair 12. The body may be dressed with a 10 waistcoat 13, collar 14, coat 15 having flat and flexible arms 16 and, in addition thereto, flat and flexible legs 17 may be connected to the head 8 and they will preferably be of the same material as said head 8 to have the 15 appearance of being covered by trousers. When the sphere or ball 6 is in the head 8, it distends said head and gives the same the appearance of the lower portion of the torso of the toy and, similarly, when said 20 sphere enters the flexible head 7, it distends said head. Other forms of dress may be resorted to and modifications employed within the spirit and scope of the invention.

When the toy is placed on an incline, as 25 shown at 18, for instance, Fig. 1, it will either slide down said incline without tumbling, if the angle of inclination is not suitable or, if the angle of inclination is just right, the rolling of the sphere or ball 6 30 from end to end of the tube 1 and its impactive reception in the heads 7 and 8 will cause the toy to have an end-over-end or tumbling action which is very grotesque and amusing.

35 Having thus described my invention, what

I claim as new and desire to secure by Letters Patent, is:—

1. In a tumbling toy, the combination of a tube or cylinder open at both ends, of cloth, fabric or similar heads or ends for the 40 cylinder, and a ball or sphere arranged to roll within the cylinder into the cloth or fabric heads or ends thereof.

2. In a tumbling figure toy, the combination with a cylinder having both of its ends 45 open, of a cloth, fabric or similar end for the head portion of the toy, and a cloth, fabric or similar end for the other end of the cylinder and arranged to constitute the 50 lower portion of the body thereof, and a ball or sphere adapted to roll in said cylinder and into the cloth, or fabric ends thereof to thereby distend the said ends.

3. In a tumbling figure toy, the combination with a tube or cylinder which is open 55 at its inner end and has a head portion at its outer end, of a cloth, fabric or similar covering, closure or pouch for the open inner end of the cylinder which constitutes the lower portion of the body of the figure, and 60 a ball or sphere adapted to roll in said cylinder and into the said end or pouch and adapted to distend said end or pouch.

In testimony whereof, I hereunto affix my signature in presence of two witnesses.

BLANCH VIE-THEER.
